COMBINED HYDRODESULFURIZATION AND REFORMING PROCESS

Clyde H. O. Berg, Long Beach, Calif., assignor to Union Oil Company of California, Los Angeles, Calif., a corporation of California

Application March 22, 1954, Serial No. 417,569

9 Claims. (Cl. 208—99)

This invention relates to an improved process and apparatus for the continuous treating or contacting of fluids with a recirculating stream of solid granular contact material and in particular relates to the conversion of petroleum and other hydrocarbons in the presence of a recirculated stream of granular hydrocarbon conversion catalyst. In its most specific embodiment this invention contemplates an improved combination process and apparatus for the simultaneous treatment of two hydrocarbon fractions of substantially different properties, such as the catalytic reforming of naphtha or gasoline fractions and the catalytic desulfurization, denitrogenation, and deoxygenation of the reformed naphtha and a gas-oil fraction in the presence of a special catalyst which has reforming, desulfurization, denitrogenation and deoxygenation activity and in which the hydrocarbon conversions cooperate with one another in an integrated process of increased efficiency.

The prior practice in hydrocarbon oil refining includes many catalytic operations wherein hydrocarbon fractions are treated and converted in a variety of processes to improve various physical and chemical properties thereof. Many hydrocarbon fractions contain undesirable impurities in the form of hydrocarbon derivatives of sulfur, nitrogen, and oxygen which render them unfit for their intended uses such as cracking stock, internal combustion engine fuels, and the like. In addition, the naphtha or gasoline fraction of these hydrocarbons contain insufficient quantities of hydrocarbon types having high antiknock characteristics and extensive refining operations are effected to increase the quantity of aromatic and branched chain hydrocarbons in these gasoline fractions to make them suitable for use as fuels in high compression engines. Accordingly, modern refining practice tends more and more toward catalytic treatment of such hydrocarbon fractions to remove undesirable fractions and to impart desirable characteristics thereto by such specific processes as catalytic desulfurization, catalytic denitrogenation, and catalytic reforming which involve paraffin hydrocarbon isomerization, dehydrogenation and cyclization, and naphthene hydrocarbon dehydrogenation to produce homologs of benzene which have high antiknock characteristics. The removal of hydrocarbon derivatives of oxygen, nitrogen and sulfur are required to produce a sweet non-corrosive product having a high lead susceptibility and to avoid problems of corrosion.

The desulfurization and denitrogenation of the naphtha and gas-oil fractions of crude petroleum ordinarily require reaction temperatures ranging from about 575° F. to about 900° F., pressures between about 50 p.s.i. (pounds per square inch) to about 5000 p.s.i. in the presence of a recycled stream of hydrogen. The hydrocarbon compounds of sulfur, nitrogen, and oxygen are decomposed forming a hydrocarbon and either hydrogen sulfide, ammonia or water. In the reforming of low-grade gasoline fractions, the naphtha vapor is contacted with a reforming catalyst at temperatures between about

2

800° F. and about 1100° F. at pressures in substantially the same range as for desulfurization, and in the presence of a hydrogen gas recycle. Although desulfurization, denitrogenation, and reforming all have desirable beneficial effects upon low-grade gasoline, the difference between the optimum reaction temperatures of these processes and the fact that the hydrogen sulfide, ammonia, and water contaminate the hydrogen recycle stream employed in the first-named operation, have heretofore necessarily required that these operations be effected entirely separately under conditions requiring separate gas plants, and unduly complicated processing steps and apparatus.

It has been found that granular catalyst of the cobalt molybdate type, supported on activated alumina carriers and analyzing between about 2% and 10% by weight of cobalt oxide (CoO) and between about 5% and about 30% by weight of molybdenum trioxide (MoO₃), is highly stable, rugged, and relatively inert to materials which conventionally poison reforming and desulfurization catalysts. It has also been found that catalysts of this type are simultaneously highly active in promoting the reactions involved in hydrocarbon desulfurization, denitrogenation, deoxygenation, and reforming.

Accordingly, the present invention is directed to a novel and highly efficient integrated process wherein low-grade naphtha or gasoline fractions are catalytically reformed under optimum reforming conditions and gas-oil fractions are desulfurized and denitrogenated also at optimum reaction conditions simultaneously in a single contacting column of unique design and in the presence of one granular catalyst consisting essentially of cobalt molybdate which is recirculated through the column. By means of a particular scheme of simultaneous operation of the desulfurizing and reforming zones in the contacting column, more specifically defined below, it is found that there exists apparently an active cooperation between the two operations whereby novel and unexpected results have been obtained and which are apparently unobtainable when the two operations are conducted separately.

It is therefore a primary broad object of the present invention to provide a new and improved fluid-solids contact process.

It is a more specific object of this invention to provide an improved integrated hydrocarbon conversion process for the simultaneous desulfurization and reforming in a single contacting column.

It is an additional object of this invention to provide in a single contacting zone a downwardly moving bed of granular cobalt molybdate catalyst and in which contacting zone a naphtha fraction is reformed in the lower portion thereof and then the reformed naphtha and a contaminated gas-oil fraction, containing hydrocarbon derivatives of sulfur, nitrogen and/or oxygen, are simultaneously treated in the upper portion of the contacting zone for the desulfurization, denitrogenation, and deoxygenation thereof.

It is a more specific object of this invention to provide in a hydrocarbon conversion process an improved contacting operation wherein the moving bed of conversion catalyst is first passed into the upper end of the contacting zone, then passed downwardly through a desulfurization zone and, is then divided into two catalyst streams, one of which is passed directly into and through a subjacent reforming zone and the other of which is passed downwardly through said reforming zone in indirect heat exchange relation thereto, and then the streams are combined for passage through a subsequent stripping and reforming zone.

It is an additional object of this invention to provide in a hydrocarbon conversion process employing a recirculated solid catalyst stream a novel and improved

catalyst elutriation step for solids fines removal, and a novel hydrogen pretreatment step which substantially eliminates from the reactor effluent elemental sulfur and sulfur containing compounds.

It is also an object of this invention to provide an apparatus for accomplishing the aforementioned objects.

Other objects and advantages of this invention will become apparent to those skilled in the art as the description thereof proceeds.

Briefly the present invention comprises an improved combination process for the simultaneous desulfurization, denitrogenation, and deoxygenation (heretofore and hereinafter referred to collectively as desulfurization) of gas-oil and naphtha hydrocarbon fractions simultaneously with the reforming of the naphtha fraction in a single contacting column or zone which includes isolated and yet communicating desulfurization and reforming zones through which a moving bed of granular catalyst is passed. Preferably the granular catalyst is of the cobalt molybdate type referred to above which has reforming and resulfurization activity. The contacting zone employed in the present invention is provided with a desulfurization zone in the upper portion and a reforming zone in the lower portion and a moving bed of granular cobalt molybdate catalyst passes downwardly by gravity through each zone. The spent catalyst removed from the contacting zone and containing a deactivating hydrocarbonaceous deposit is recirculated to the top of the contacting zone through a regeneration zone in which the hydrocarbonaceous deposit is burned from the catalyst to restore its former activity.

The modification of this invention illustrated in the figure involves the passage of the entire catalyst stream downwardly as a moving bed through the desulfurization zone, and then dividing the spent catalyst into a primary and a secondary stream. The primary stream is then introduced directly into the reforming zone wherein it passes downwardly as a moving bed and the other stream is passed downwardly indirectly through and in indirect heat exchange relationship with the bed of catalyst in the major portion of the reforming zone. The two streams are combined in the lower portion of the reforming zone to re-establish the entire catalyst stream which contacts the freshly introduced naphtha reactant mixture for naphtha stripping. The spent catalyst is then steam stripped and removed from the system for regeneration. This modification of the invention is especially well adapted to the desulfurization of heavily contaminated gas-oils requiring large amounts of hydrogen simultaneously with the reforming of relatively naphthenic gasolines which produce large quantities of hydrogen.

In the process of this invention, the endothermic reactions characterizing naphtha reforming and the exothermic reactions occurring during desulfurization, denitrogenation and deoxygenation in the desulfurization zone, normally result in the generation and maintenance of temperature gradients if the reaction zones are permitted to operate adiabatically. Reforming reaction rates decrease significantly with relatively small decreases in temperature and difficulty controllable hydrogenation reactions may occur if the temperature is permitted to increase unduly in the desulfurization zone. Accordingly, in the present invention the reacting mixture of naphtha and hydrogen is preferably heated at one or more points along the length of the reforming zone and the reacting mixture of gas-oil and naphtha vapor and hydrogen is cooled at one or more points along the length of the desulfurization zone to maintain the average reaction temperature in each of said zones substantially uniform at the optimum value.

In the reforming zone of the process of the present invention, naphtha vapor and between about 500 and 10,000 s.c.f. of hydrogen per barrel of naphtha are passed in contact with a cobalt molybdate catalyst at a liquid

hourly space velocity (L.H.S.V.) of between about 0.2 and 2.0, at temperatures between about 800° F. and 1000° F., preferably about 900° F., and at a pressure of between 50 p.s.i. and 5000 p.s.i., preferably between about 50 and 1000 p.s.i. such as about 400 p.s.i. to dehydrogenate and cyclize paraffin hydrocarbons and to dehydrogenate naphthene hydrocarbons to produce a highly aromatic reformed gasoline product containing branched chain hydrocarbons and having a knock rating of above 92. Heat is added along the length of the reforming zone to maintain a uniform temperature profile therein by means more fully described below. The reformed naphtha and the recycle hydrogen stream, which now contains excess hydrogen produced during the reforming, is mixed with the gas-oil to be treated. The gas-oil may be partly or completely vaporized, but in any event is preferably at a temperature whereby admixture with the effluent from the reforming zone will produce a mixture having a temperature of about 775° F., which is the optimum preferred gas-oil and naphtha desulfurization temperature.

This mixture of gas-oil, naphtha and hydrogen is passed at the reduced temperature of from about 575° F. to 900° F., at an L.H.S.V. between about 0.2 and 15.0, at substantially the same pressure and with from 50 to 5000 s.c.f. of hydrogen per barrel of hydrocarbon, through the desulfurization zone wherein the naphtha and gas-oil are simultaneously desulfurized, denitrogenated, and deoxygenated to produce respectively, hydrogen sulfide, ammonia, and water vapor. The hydrocarbons remaining are hydrogenated to stable hydrocarbon products maintaining a high liquid product yield. These reactions consume the excess hydrogen which was generated as described during the reforming step. In doing so, considerable heat is liberated and accordingly the reactant mixture is preferably cooled at one or more points along the length of the desulfurization zone so as to maintain the optimum desulfurization temperature.

In a preferred modification of the operation of this process, the naphtha and gas-oil feed rates are balanced against one another as a function of the naphthene hydrocarbon content of the gasoline and of the sulfur, nitrogen, and oxygen content of the gas-oil so that during the reforming step the naphthene dehydrogenation proceeds sufficiently to liberate a quantity of hydrogen which is equal to or greater than that necessary to fully desulfurize, denitrogenate, and deoxygenate both the gas-oil and the naphtha. Thus a hydrogen balance is reached and no outside sources of hydrogen are required. This is one of the advantages of the present invention which, together with the requirement of only a single catalyst, namely cobalt molybdate, the means for temperature control in the desulfurization and reforming zones, the use of separate cobalt molybdate catalyst streams within a single contacting zone to treat two hydrocarbon streams, the naphtha stripping of the combined catalyst streams to permit total recovery of gas-oil thereby eliminating the usual 10% gas-oil loss, and the subsequent steam stripping of the spent catalyst to recover the naphtha therefrom, yields an integrated process which permits simultaneous treatment of two related hydrocarbon fractions to produce premium-grade internal combustion engine fuels. By locating the desulfurization zone above the reforming zone and subsequently passing the spent desulfurization catalyst stream through the reforming zone, either directly or indirectly, the temperature of the spent desulfurization catalyst is raised in the presence of a naphtha and hydrogen flow which has been found to permit the highly efficient stripping of gas-oil from the catalyst with substantially no loss due to catalytic cracking. In the modification shown in the figure wherein spent catalyst from the desulfurization zone passes indirectly through the reforming zone, the same effect results in that the catalyst is gradually heated within the tubes and

in the presence of a small countercurrent flow of naphtha and hydrogen which passes upwardly therethrough.

The mixture of gas-oil, naphtha, and hydrogen is removed from the reactor effluent at the top of the contacting zone, cooled, partially condensed, and the vapor remaining is separated from the liquid. The gas fraction contains recycle hydrogen together with hydrogen sulfide, ammonia, and water vapor which may be separated from the recycle hydrogen by conventional means. It is preferred that the hydrogen recycle contain at least 25% hydrogen by volume and preferably more than 70% hydrogen by volume. The liquid fraction comprises a mixture of naphtha and gas-oil which is substantially free of sulfur, nitrogen, and oxygen and the naphtha fraction of which consists essentially of branched chain paraffin hydrocarbons and aromatic hydrocarbons and is an excellent blending stock for premium and aviation gasolines.

In the process of the present invention, it has been found that the required catalyst recirculation is low and the permissible on-stream time of the catalyst is long and therefore the regeneration of the catalytic material is quite simple. Although the spent catalyst removed from the bottom of the contacting zone may be passed through a separate regeneration zone in which the solids flow downwardly as a moving bed, it is a preferred form of this invention to convey the granular solids from the bottom to the top of the column through an elongated conveyance conduit in which the granular solids are maintained in compact dense-packed form, that is, as a mass having a bulk density substantially equal to the static bulk density of the solids when at rest. The conveyance fluid employed is a regeneration gas such as a mixture of flue gas to which air or oxygen has been added to produce a regeneration gas mixture containing between about 1% and about 5% oxygen by volume at the bottom of the lift line. This combination conveyance-regeneration gas is passed through the conveyance zone at a rate sufficient to convey the granular solids upwardly as a compact mass. The fluid and the solids flow concurrently at a relatively low rate and are regenerated during conveyance. The spent regeneration gases are removed at the top of the conveyance conduit, and the regenerated solids are circulated into the top of the contacting zone.

It has been found that in spite of the regeneration of the catalyst, from 20 to 40% of the sulfur present on the spent catalyst remains, possibly in the form of cobalt or molybdenum sulfides or the like, the constitution of which is not known. It has been determined that when such regenerated catalyst is introduced directly into the desulfurization zone and contacts the hydrogen sulfide-containing gas there, the hydrogen sulfide in some way reacts with the sulfided regenerated catalyst to produce elemental sulfur. This sulfur is carried out with the reactor effluent and renders the product sour and corrosive. It has been found that by treating the regenerated catalyst with a countercurrent stream of hydrogen recycle gas substantially free of hydrogen sulfide, the sulfur on the catalyst is liberated as sulfur and sulfur dioxide in a reaction generating considerable heat, and the presence of elemental sulfur in the product is fully eliminated. The character of the reaction is not fully understood, but its effect upon the physical properties of the product is remarkable for the effluent gasoline is sweet.

The conveyance of spent catalyst to a separate regeneration zone and its regeneration therein during downward flow therethrough as a moving bed is conventional and will not be described in further detail. However, the modification wherein the spent catalyst is conducted upwardly as a moving bed through a conveyance-regeneration zone is a novel type of regeneration and the details of its operation will be briefly described below.

The pressure drop characteristic of this type of solids conveyance is of the order of 100 times that characteristic of pneumatic or gas lift (suspended) solids convey-

ance and the volume of gas required to convey dense-packed solids is only a few percent of that required in gas lift. The granular solids to be conveyed are removed from the bottom of the contacting column at substantially the reforming pressure, are passed through a solids pressuring zone to increase the pressure of gases associated with the solids by an amount substantially equal to the characteristic pressure drop of the conveyance conduit, and then the solids are passed into the conveyance element of the apparatus.

The inlet of the conveyance-regenerator conduit is thus maintained at a relatively higher pressure generally than the pressure of the solids before introduction into the conveyance conduit. The granular solids are then transferred through the conveyance conduit in compact dense-packed form by means of a concurrently depressurizing conveyance-regeneration fluid. The frictional forces generated by the fluid depressurizing through the interstices of the compact mass of solids generate a pressure gradient in the conduit sufficient to counteract opposing forces of friction of the solids sliding against the walls of the conduit as well as the opposing force of gravitation and thereby establish a conveying force permitting movement of the compact porous granular mass in the direction of decreasing conveyance fluid pressure when solids are removed from the outlet and fed into the inlet.

The depressurizing conveyance fluid generates a pressure drop per unit length of conduit

$$\frac{dp}{dl}$$

(the pressure gradient) sufficient to overcome the opposing gravitational force ($\rho_s \cos \theta$), wherein ρ_s is the bulk density of the dense-packed granular solids and θ is the angular deviation of the conveyance conduit from the vertical. The ratio of the former to the latter is

$$\frac{dp}{dl} \over \rho_s \cos \theta$$

This factor is termed the conveyance force ratio and is the ratio of the force tending to move the solids through the conveyance conduit to the opposing forces of gravity tending to restrain such flow. The conveyance fluid must be depressed through the conduit at a rate sufficient to raise the conveyance force ratio to a value greater than 1.0 (factors in consistent units) in order that the conveying force exceed the forces resisting flow. The amount by which the conveyance force ratio must exceed a value of 1.0 is equal to the magnitude of the friction forces also tending to resist solids flow.

The granular solids are maintained during conveyance and regeneration in the compact form by means of the application of a compressive force on the discharge solids issuing from outlet of the conveyance conduit. Various means are available for applying such a force which has the effect of restricting the discharge rate of granular solids from the conveyance conduit but has virtually no effect on the discharge of the conveyance fluid therefrom. A transverse thrust plate or a grid may be spaced opposite and adjacent the outlet opening and against which the mass of solids discharges, or a static bed of solids may be used to submerge this outlet. The rate of solids conveyance is determined by the rate of solids removal from the contacting column which is full of dense-packed solids in the form of a moving bed. The solids feeder at the column bottom controls this variable as described below.

The present invention will be more clearly understood by reference to the accompanying drawings in which:

Figure 1 is a schematic flow diagram of the process of this invention including an elevation view in cross section showing the details of the contacting column,

Figure 2 shows a cross-sectional view of the detail of the top part of the structure of Figure 1.

Referring now more particularly to Figure 1, contacting column 10 is divided into three major contacting zones including first treating or desulfurization zone 12, second treating or reforming zone 14, and combination third treating or reforming and stripping zone 16.

Contacting column 10 is provided at successively lower levels therein with treating gas injection zone 96, hopper and seal zone 18, effluent disengaging zone 20, second desulfurization zone 22, cooling zone 24, first desulfurization zone 26, gas-oil engaging and naphtha mixing zone 28, third reforming zone 32, heating zone 34, second reforming zone 36, first and second catalyst stream rate control zone 38, first reforming and naphtha stripping zone 40, naphtha engaging zone 42, hydrogen stripping zone 43, hydrogen engaging zone 44, stripping zone 45, stripping gas engaging zone 46, and catalyst feeder zone 48.

The granular catalyst introduced into hopper zone 18 through inlet 94 passes entirely through desulfurization zone 12 as a downwardly moving bed by gravity. The spent catalyst is divided at the bottom of the desulfurization zone into a primary and secondary portion just above the point of gas-oil injection through line 208 into engaging zone 28. The primary portion passes downwardly directly into and through reforming zone 14 and is removed therefrom through conduits 58 at a rate controlled by valves 60. The secondary portion is bypassed indirectly through and in indirect heat exchange relationship to reforming zone 14 through secondary tubes 54 at a rate controlled by valves 56. The spent catalyst is combined into a single stream prior to passage through first naphtha reforming and stripping zone 40 in which the fresh naphtha feed thoroughly strips any residual gas-oil from the catalyst picked up during passage through the desulfurization zone. It is not necessary that these control elements be valves, for orifices of fixed or variable area may be substituted at this point in the apparatus so as to control the relative solids flow rate. Orifices are entirely effective since the flow of solids through an orifice is substantially unaffected by the depth of the bed of solids above the orifice provided this depth is greater than two or three orifice diameters. Since the flow of solids through an orifice is inhibited by countercurrent fluid flow therethrough, vapor risers and caps 62 are provided which effectively bypass the reactant naphtha through caps 62 thus preventing any vapor flow interference with the solids flow in conduits 58.

The absolute circulation rate of granular solids through column 10 is fixed by reciprocating tray solids feeder 48 located in the bottom of the column. The details of this apparatus element are not shown because they are well-known in the art. This element also provides for a uniform removal of spent catalyst throughout the entire cross-sectional area of the column and this uniformity of solids flow is reflected entirely throughout the height of the column when primary tubes 58, secondary tubes 54, and the other tubular elements of this apparatus are uniformly distributed throughout the cross-sectional area of the column.

The combined stream of spent granular solids passes downwardly into solids pressuring means 66 in which the spent granular catalyst is pressured from the reaction pressure to a higher pressure exceeding the reaction pressure by an amount substantially equal to the required pressure differential for conveying the spent catalyst as a substantially compact upwardly moving bed through conveyance-regeneration conduit 68. The details of solids pressuring means 66 are not shown for they are described in copending application Serial No. 217,337, filed March 24, 1951, now U.S. Patent No. 2,695,212. The spent catalyst is pressured by means of high pressure gas, preferably inert such as oxygen-free flue gas, introduced through line 70 controlled by valve 72. The thus pressured solids then are passed downwardly to submerge inlet opening 74 of the conveyance-regeneration zone. A

conveyance-regeneration gas, containing between about 1% and about 5% by volume of oxygen, is introduced through line 76 at a rate controlled by valve 78 and passes downwardly concurrently with the pressured spent catalyst which flows by gravity into inlet opening 74, or the oxygen concentration in line 68 may be maintained by injection of the oxygen containing gas directly into the line as through line 71 controlled by valve 73. This conveyance-regeneration fluid is depressed concurrently through conveyance-regeneration zone 68 as described above and the spent catalyst is simultaneously conveyed and regenerated during transit upwardly through the conveyance-regeneration zone. In the present process, the catalyst circulation rate is quite low and the heat generated by regeneration may be carried out of the system with the spent regeneration gases as subsequently described, or a jacket or vessel may be provided surrounding conveyance zone 68 whereby a coolant may be passed around zone 68 to remove heat in this way.

The spent regeneration gases discharging from zone 68 with the regenerated solids preferably contain less than 1% oxygen. The regenerated catalyst discharges into solids-receiving and elutriation zone 80 directly against baffle 82 whereby the solids thrust or compacting force is applied to the discharging catalyst preventing its fluidization and maintaining the granular solids during conveyance and regeneration at a bulk density substantially equal to the bulk density of the downwardly moving bed of catalyst in contacting column 10. The spent regeneration gas is disengaged from the solids through inclined surface 87 of the discharged solids and is removed from the top of solids-receiving zone 80 through outlet 81 and aperture 83 and line 84 at a rate controlled by valve 86 which is actuated by back pressure regulator 88. These gases, in being disengaged from the discharged solids, act as an elutriation medium and suspend and carry out solids fines. The degree of elutriation is variable, as described in connection with Figure 2 by varying the area open to gas disengagement. The regeneration elutriation gas is removed at substantially the same pressure as the operating pressure in contacting column 10, and may be repressured and recirculated through the regeneration zone with added oxygen.

Referring now to Figure 2, a plan view in cross section of solids-receiving chamber 80 is shown. Herein are shown the crossed vertical baffles 79 extending downward into the discharged solids forming 4, 6, 8, or more individual circularly disposed elutriation chambers of pie-shaped cross section. Only 4 chambers are shown for purposes of illustration. Gas outlet 81 is provided centrally, between the individual chambers, and is provided with one or more openings 83. Thus, with one such opening, only the solids disengaging area in one individual chamber is active and the gas velocity therein is relatively high because of the relatively constant conveyance-regeneration gas flow through the lift line and the thus reduced area of solids through which it is disengaged. By using more such openings, more of the individual elutriation chambers actively disengage gas and the disengagement velocity is lower. With the greater velocities of disengagement larger solids fines are suspended and carried out, and reductions in velocity as described reduce the size of the particles suspended and removed.

The regenerated cobalt molybdate catalyst, freed of solids fines, passes downwardly in the form of compact bed 90 downwardly over treating gas disengaging zone 92 and then downwardly through inlet conduit 94 into the top of column 10. The lower opening of inlet 94 is surrounded by treating gas injection collar 96. Hydrogen sulfide-free recycle hydrogen is introduced by means of line 98 at a rate controlled by valve 100 and flow recorder controller 102 into collar 96. This treating gas splits into two streams, the first passing downwardly concurrently with the catalyst through hopper zone 18, and the second passing upwardly through inlet 94 and through

treating zone 104 in the lower portion of solids-receiving zone 80. This latter hydrogen stream countercurrently contacts the regenerated catalyst, causes the liberation therefrom of the residual quantities of sulfur in the form of sulfur and sulfur dioxide which are removed from treating gas disengaging zone 92 through line 106 at a rate controlled by valve 108 in accordance with differential pressure controller 110 which maintains a positive pressure differential between the extremities of inlet zone 94. This differential pressure is quite small, of the order of a few inches of water and serves to seal the top of the column against hydrogen sulfide contacting the regenerated catalyst. In this manner the reactor effluent is maintained entirely free of elemental sulfur and in this way a long standing problem has been eliminated whereby the conventional post treating operations on the product to render it sweet and non-corrosive are avoided.

The remainder of the description of Figure 1 will be conducted as an illustrative example in which a straight run naphtha and a straight run gas-oil are simultaneously treated by the process of this invention. Both the naphtha and the gas-oil are heavily contaminated with sulfur and nitrogen and their physical properties are as follows:

TABLE 1
Naphtha feed

Gravity, °API	49.8
Boiling range, °F.	200-400
Sulfur, weight percent	0.10
Nitrogen, weight percent	0.003
Knock rating, F-1 Clear	57

TABLE 2
Gas-oil feed

Gravity, °API	24.5
Boiling range, °F.	500-900
Sulfur, weight percent	3.76
Nitrogen, weight percent	0.24

The naphtha feed rate is 1000 barrels per day and the gas-oil feed rate is 500 barrels per day. The total catalyst circulation rate is 14 tons per day, the rate through the desulfurization zone being 14 tons per day, and the rate through the reforming zone being 10 tons per day. The desulfurization and reforming zones are operated at a pressure of about 400 p.s.i.a. (pounds per square inch absolute), the temperature of the reforming zone is maintained at an average of 900° F. and the temperature of the desulfurization zone is maintained at an average of 750° F.

The naphtha feed passes from storage through line 120 by means of naphtha feed pump 122 at the above-mentioned rate controlled by valve 124 and flow recorder controller 126 through line 128 and interchanger 130. Herein the cold feed is exchanged with part of the reactor effluent described below and is raised to a temperature of 600° F. The preheated naphtha then flows through line 132 through naphtha preheating and vaporizing coil 134 in furnace 136. The naphtha vapor then passes by means of line 138 into naphtha engaging zone 42.

Recycle hydrogen, necessary in the operations conducted in this process and separated from the reactor effluent as described below, flows through line 140 into gas purifier 142. Herein, by conventional means, hydrogen sulfide, ammonia, and water vapor are separated from the recycle gas and if desired any low molecular weight hydrocarbon gas which may be present such as methane, ethane, and the like may also be removed through line 143. The hydrogen thus treated then flows through line 144 together with additional hydrogen, if necessary, injected through line 146 controlled by valve 148 and is pumped by means of recycle blower 150 at a rate controlled by valve 152 and flow recorder controller 154 through hydrogen heating coil 156 in furnace 136. The heated hydrogen, at a temperature of about 900° F.

passes through line 158 at a rate of 3000 M s.c.f./d. (thousand standard cubic feet per day) into hydrogen recycle engaging zone 44. Under the influence of a seal or stripping gas such as steam introduced through line 160 controlled by valve 162 into engaging zone 46 at a slightly higher pressure, substantially all of the hydrogen recycle gas passes upwardly from zone 44 and is combined with naphtha vapor in engaging zone 42 to form a reactant naphtha and hydrogen mixture which passes through the reforming zone as described in detail below. The reactant mixture of naphtha and hydrogen passes upwardly through first reforming and naphtha stripping zone 40 countercurrent to the combined catalyst streams. Herein the initial catalytic reforming of the naphtha takes place simultaneously with exothermic hydrogenation of any olefinic constituents in the naphtha feed. The temperature rises somewhat to values preferably not exceeding about 925° F. This maximum temperature is controlled by reducing the naphtha vapor inlet temperature so that olefin hydrogenation does not raise the temperature above a value of that given. Simultaneously in zone 40, a highly effective naphtha and hydrogen stripping of that part of the catalyst introduced therewith from desulfurization zone 12 takes place. Substantially all of the residual gas-oil present on the catalyst is removed thereby and vaporized leaving a spent reforming catalyst containing traces of adsorbed naphtha but substantially gas-oil free. As stated above, this spent catalyst is steam stripped in zone 45 immediately above stripping gas engaging zone 46 and the naphtha is returned upwardly into the reactant mixture and passes upwardly therewith. In this manner substantially no gas-oil or naphtha feed is lost by oxidation in the spent catalyst regeneration step and maximum liquid product yields of the order of 95% to 99% are obtained.

The reactant mixture of naphtha and hydrogen, together with minor amounts of gas-oil vapor stripped from the catalyst, passes upwardly through vapor risers and caps 62 into and countercurrently through second reforming zone 36. Herein additional aromatization takes place causing the temperature to drop to a value of preferably not less than 875° F. by the time it reaches heating zone 34.

At this point the naphtha reactants are reheated to a temperature of about 900° F. or slightly higher for subsequent passage through third reforming zone 32. Preferably the disengaging-engaging structure shown in the drawing is employed which consists of upper tray 166, lower tray 168 with a plurality of seal tubes 170 open at both ends and extending from above tray 166 through and to a point below lower tray 168. Seal tubes 170 pass the catalyst downwardly therethrough creating a path having a relatively high resistance to reactant vapor flow. Accordingly only a minor portion of the reactant vapor mixture passes upwardly through tubes 170 generating a pressure differential of about 1.0 p.s.i. which is sufficient to force the major portion of the mixture from lower disengaging zone 172 through line 174, into and through interheater 176 wherein the temperature is increased to compensate for the temperature drop occasioned by endothermic reforming reactions in reforming zone 36 and the prospective temperature drop in zone 32. The reheated mixture is then passed through line 178 into engaging zone 180 wherefrom it passes upwardly through vapor risers 182 into the bottom of third reforming zone 32.

Herein the reheated vapor mixture contacts reforming catalyst and additional aromatization takes place causing a further temperature decrease. The naphtha reforming zone effluent, containing aromatized naphtha vapor together with an excess of hydrogen produced during the reforming, is disengaged from the catalyst in zone 28. Fresh gas-oil, injected as described below, is mixed herein with the naphtha effluent from reforming third zone 32 and passes upwardly through vapor risers

and caps 210 to be treated simultaneously in desulfurization zone 12.

The gas-oil to be converted is introduced through line 188 and pumped by means of pump 190 at a rate of 500 barrels per day controlled by valve 192 and flow recorder controller 194. The gas-oil flows through line 196 through preheater 198 in exchange with the remaining part of the reactor effluent. The preheated gas-oil at a temperature of about 650° F. flows through line 200 into and through gas-oil heating and vaporizing coil 202 in furnace 204. Herein a partial or complete vaporization of gas-oil is effected, depending upon its end point, and the gas-oil is combined in mixing zone 28 with the naphtha-hydrogen effluent from reforming zone 14. The furnace 204 is controlled to have an outlet temperature such that upon admixture of the thus heated gas-oil with the effluent naphtha vapor flowing from third reforming zone 32, the temperature of the resulting mixture is substantially equal to the preferred desulfurization temperature, that is, about 750° F. In the present example the furnace outlet temperature was about 650° F. and the temperature of the naphtha mixture flowing into mixing zone 28 from reforming zone 32 was 900° F.

If it is desired, better mixing of the naphtha and gas-oil vapor to be desulfurized may be obtained by removing the disengaged naphtha and hydrogen from the column, mixing this stream with the gas-oil at a point outside the column, and returning the mixture to the bottom of the desulfurization zone for passage therethrough.

The reactant mixture of naphtha and gas-oil vapor and recycle hydrogen formed as above described passes upwardly from engaging zone 28 through vapor risers 210 and then through first desulfurization zone 26 countercurrent to the downwardly flowing stream of cobalt molybdate catalyst. Herein, under the temperature and pressure conditions given, the sulfur, nitrogen, and oxygen compounds are destructively hydrogenated forming the corresponding hydrocarbon derivatives together with hydrogen sulfide, ammonia, and water vapor. Depending upon the extent of gas-oil and naphtha contamination with these compounds, more or less heat is liberated in first desulfurization zone 26 and the temperature of the reactant vapor mixture rises to a value of about 780° F. after passage therethrough. In a manner entirely analogous to the disengaging and engaging of the reactant naphtha vapor described in connection with heating zone 34, the reactant mixture is disengaged, cooled, and engaged in cooling section 24. This section is provided with upper tray 212 and lower tray 214 forming disengaging zone 216 and engaging zone 218. Catalyst seal tubes 220 are equivalent to tubes 170 described above. As before, a minor portion of the reactant vapor passes upwardly through the restricted passageway formed by tubes 220 generating a pressure drop which forces the major portion from disengaging zone 216 through line 221 and intercooler 222 and then back through line 224 into engaging zone 218. In this example intercooler 222 serves to decrease the temperature of the reactant mixture to about 750° F. at which it enters second desulfurization zone 22 through vapor risers 226.

Further desulfurization takes place in second desulfurization zone 22 which serves to remove substantially all the residual sulfur, nitrogen and oxygen contaminants therein. The temperature rises somewhat to a value of about 770° F. and accumulates in effluent disengaging zone 26 from which it is removed with a small portion of hydrogen passing downwardly with the catalyst through hopper zone 18. The reactor effluent includes the naphtha and gas-oil vapors substantially free of the aforementioned contaminants together with moderate amounts of hydrogen sulfide, ammonia, water vapor, hydrogen, and small amounts of low molecular weight hydrocarbon gases.

The reactor effluent passes from disengaging zone 20 through line 228, and is divided into two streams which pass through gas-oil preheater 198 and through naphtha preheater 130. Effluent cooling and condensation takes place and then the combined streams pass through line 230 through product effluent cooler 232 and through line 234 into vapor liquid separator 236.

The condensed liquid product accumulates in the lower portion of separator 236 and is removed therefrom through line 238 controlled by valve 240 and liquid level controller 242. This liquid product contains some water and consists essentially of gas-oil and naphtha mixture. By means of conventional techniques the water is separated as by settling and decantation and the hydrocarbon product is fractionated into a gasoline fraction and a desulfurized gas-oil fraction having excellent cracking qualities and containing a large fraction of hydrocarbons suitable for 50 cetane diesel fuel or jet engine fuel. Upon such fractionation 952 barrels per day of C₄-free reformed gasoline having a 400° F. end point are obtained, amounting to a liquid naphtha yield of 95.2%. The physical properties of this gasoline are as follows:

TABLE 3

Reformed gasoline product

Gravity, ° API	50.4
Boiling range, ° F.	100-420
Sulfur, weight percent	0.002
Nitrogen, weight percent	Nil
Knock rating, F-1 Clear	85.2
Knock rating, 3 ml. TEL	91.8

The production of desulfurized gas-oil amounts to 550 barrels per day, liquid yield of gas-oil of 101%, and its physical properties are as follows:

TABLE 4

Gas-oil product

Gravity, ° API	29.1
Boiling range, ° F.	400-900
Sulfur, weight percent	0.53
Nitrogen, weight percent	0.10
Cetane No.	38.0

The uncondensed portion of the reactor effluent is removed from separator 236 through line 244 and is ordinarily divided into two streams. The first stream passes through line 140 to provide the recycle hydrogen employed in the process as described above. Any net production of hydrogen, which may result when highly naphthenic gasolines are reformed and desulfurized in the presence of a gas-oil which either contains relatively small amounts of sulfur or which is fed to the system at relatively low rates, is bled from the system through line 246 at a rate controlled by valve 248 and back pressure regulator 250 which maintains the operating pressure on the system. In the present example, the relative feed rates and compositions were such that no net hydrogen is produced and no net consumption of hydrogen takes place.

In this invention the desulfurization, which term is used to include denitrogenation and deoxygenation, takes place in the upper portion of the contacting column and the naphtha reforming is effected in the lower portion 65 of the column. In the process, one or more interheaters or intercoolers are employed in the reforming or desulfurization zones respectively depending upon the degree of uniformity of the reaction temperature desired. Only one intercooler and interheater has been shown and described, but it should be understood that as many as 8 or 10 of such heaters can be employed in the present apparatus.

Although other catalysts having desulfurization and reforming activities may be employed or a mixture of known catalysts including a desulfurization catalyst and

a reforming catalyst can also be used, the preferred catalytic agent to be used in this process is the cobalt molybdate type containing cobalt and molybdenum oxides in the amounts given above because these have been found to be extremely stable under reforming and desulfurization conditions and in addition have been found to have very high activities for reforming, desulfurization, denitrogenation, and deoxygenation properties which are not found in other known catalysts.

Cobalt molybdate catalysts in general comprise mixtures of cobalt and molybdenum oxides wherein the molecular ratio of CoO to MoO_3 is between about 0.4 and 5.0 and are prepared as described below. This catalyst may be employed in unsupported form or alternatively it may be distended on a suitable carrier such as alumina, silica, zirconia, thoria, magnesia, magnesium hydroxide, titania or any combination thereof. Of the foregoing carriers it has been found that the preferred carrier material is alumina and especially alumina containing about 3-8% by weight of silica.

In the preparation of the unsupported cobalt molybdate, the catalyst can be coprecipitated by mixing aqueous solutions of, for example, cobalt nitrate and ammonium molybdate, whereby a precipitate is formed. The precipitate is filtered, washed, dried and finally activated by heating to about 500°C .

Alternatively, the cobalt molybdate may be supported on alumina by coprecipitating a mixture of cobalt, aluminum and molybdenum oxides. A suitable hydrogel of the three components can be prepared by adding an ammonical molybdate solution to an aqueous solution of cobalt and aluminum nitrates. The precipitate which results is washed, dried and activated.

In still another method, a washed alumina hydrogel is suspended in an aqueous solution of cobalt nitrate and an ammoniacal solution of ammonium molybdate is added thereto. By this means a cobalt molybdate gel is precipitated on the alumina gel carrier.

Catalyst preparations similar in nature to these and which can also be employed in this invention have been described in U.S. Patents 2,369,432 and 2,325,033.

Still other methods of catalyst preparation may be employed such as by impregnating a dried carrier material, e.g. an alumina-silica gel, with an ammoniacal solution of cobalt nitrate and ammonium molybdate. Preparations of this type of cobalt molybdate catalyst are described in U.S. Patent 2,486,361.

In another method for preparing impregnated molybdate catalyst the carrier material may be first impregnated with an aqueous solution of cobalt nitrate and thereafter impregnated with an ammoniacal molybdate. Alternatively, the carrier may also be impregnated with these solutions in reverse order. Following the impregnation of the carrier by either of the foregoing methods the material is drained, dried and finally activated in substantially the same manner as is employed for the other catalysts.

In the preparation of impregnated catalysts where separate solutions of cobalt and molybdenum are employed, it has been found that it is preferable to impregnate the carrier first with molybdenum, e.g., ammoniacal ammonium molybdate, and thereafter to impregnate with cobalt, e.g., aqueous cobalt nitrate, rather than in reverse order.

In another method for the preparation of suitable catalyst, a gel of cobalt molybdate can be prepared as described hereinbefore for the unsupported catalyst, which gel after drying and grinding can be mixed with a ground alumina, alumina-silica or other suitable carrier together with a suitable pilling lubricant or binder which mixture can then be pilled or otherwise formed into pills or larger particles and activated.

In another modification, finely divided or ground molybdc oxide can be mixed with suitably ground car-

rier such as alumina, alumina-silica and the like in the presence of a suitable lubricant or binder and thereafter pilled or otherwise formed into larger agglomerated particles. These pills or particles are then subjected to a preliminary activation by heating to 600°C . for example, and are thereafter impregnated with an aqueous solution of cobalt nitrate to deposit the cobalt compound thereon. After draining and drying, the particles are heated to about 600°C . to form the catalyst.

It is apparent from the foregoing description of the different types of cobalt molybdate catalyst which may be employed in this invention that we may employ either an unsupported catalyst, in which case the active agents approximate 100% of the composition, or we may employ a supported catalyst wherein the active agents, cobalt and molybdenum oxides, will generally comprise from about 7 to 22% by weight of the catalyst composition. In all of the foregoing catalytic preparations it is desirable to maintain the molecular ratio of cobalt oxide as CoO to molybdc oxide as MoO_3 between about 0.4 and 5.0.

A particular embodiment of the present invention has been described in considerable detail by way of illustration. It should be understood that various other modifications and adaptations thereof may be maintained by those skilled in the particular art without departing from the spirit and scope of this invention as set forth in the appended claims.

I claim:

1. In a moving-bed isobaric catalytic contacting process wherein granular reforming and desulfurization catalyst is circulated downwardly through an upper low-temperature desulfurization zone and then through a subjacent high-temperature reforming zone, and wherein naphtha plus hydrogen is contacted countercurrently with the catalyst in said reforming zone, and the reformed naphtha is then admixed with a gas oil and the resulting mixture of gas oil, naphtha and hydrogen is then passed upwardly through said desulfurization zone to effect desulfurization, the improved method for obtaining controlled relative catalyst treating capacity in each of said contacting zones while still effectively utilizing said naphtha feed to strip residual gas oil from all of said catalyst prior to regeneration, which comprises passing a controlled first portion of the catalyst from said desulfurization zone through the upper major portion of said reforming zone in indirect heat-exchange therewith and out of contact with the major stream of naphtha flowing therethrough, passing the remainder of said catalyst from the desulfurization zone through the entire reforming zone in contact with said naphtha, and recombining said first portion of catalyst with said remainder of catalyst in the lower portion of said reforming zone, whereby the relative amount of catalytic reforming capacity is readily controllable in response to variations in quantity and nature of feeds, and the entire catalyst stream is effectively stripped of residual gas oil by the naphtha and hydrogen vapors in said lower portion of the reforming zone.

2. A process as defined in claim 1 wherein the temperature profile in said reforming zone is maintained relatively uniform by withdrawing reactant naphtha vapors therefrom at at least one intermediate point along the length thereof, heating said withdrawn portion to the desired reforming temperature, and then reintroducing the reheated vapors downstreamwardly in said reforming zone.

3. A process as defined in claim 1 wherein the quantity of said first portion of catalyst which is diverted through the reforming zone in indirect heat-exchange therewith is controlled to provide approximately the necessary reforming capacity per hour in said remaining stream of catalyst to effect sufficient reforming and net hydrogen production to balance approxi-

mately the net hydrogen consumption in said desulfurization zone.

4. A process as defined in claim 1 wherein said catalyst consists essentially of a minor proportion of cobalt oxide plus molybdenum oxide supported on a carrier which is predominantly activated alumina. 5

5. A process as defined in claim 1 wherein said desulfurization zone is maintained at a temperature between about 575° and 900° F., and said reforming zone is maintained at a temperature between about 800° and 1000° F., and wherein both of said zones are maintained at substantially the same pressure within the range of about 50 to 5,000 p.s.i.g. 10

6. A process as defined in claim 1 wherein said first portion of catalyst is passed through said reforming zone by means of at least one vertical conduit extending through the upper portion of said reforming zone. 15

7. A process as defined in claim 1 wherein the combined stripped catalyst from said reforming zone is subjected to oxidative regeneration and then recycled to said desulfurization zone. 20

8. A process as defined in claim 7 wherein said regeneration is effected in a compact-flow lift line simultaneously with the conveyance thereof by the use of oxygen-containing lift gas at regeneration temperatures. 25

9. In a moving-bed isobaric catalytic contacting process wherein granular reforming and desulfurization catalyst is circulated downwardly through an upper low-temperature desulfurization zone and then through a subjacent high-temperature reforming zone, and wherein a low-boiling hydrocarbon plus hydrogen is contacted countercurrently with the catalyst in said reforming zone to effect reforming with a net production of hydrogen, and the reformed product is then admixed with a high-boiling hydrocarbon and the resulting mixture containing hydrogen is then passed upwardly through said desulfurization zone to effect desulfurization, the improved method for obtaining controlled relative catalyst treating capacity in each of said contacting zones while still effectively utilizing said low-boiling hydrocarbon feed to strip residual high-boiling hydrocarbon from all of said catalyst prior to regeneration, which comprises passing a controlled first portion of the catalyst from said desul- 30

40

furization zone through the upper major portion of said reforming zone in indirect heat-exchange therewith and out of contact with the major stream of low-boiling hydrocarbon flowing therethrough, passing the remainder of said catalyst from the desulfurization zone through the entire reforming zone in contact with said low-boiling hydrocarbon, and recombining said first portion of catalyst with said remainder of catalyst in the lower portion of said reforming zone, whereby the relative amount of catalytic reforming capacity is readily controllable in response to variations in quantity and nature of feeds, and the entire catalyst stream is effectively stripped of residual high-boiling hydrocarbon by the low-boiling hydrocarbon vapors and hydrogen in said lower portion of the reforming zone. 15
